INTERMITTER TIMING DEVICE

William R. King, Mineola, Tex.

Application April 14, 1942, Serial No. 438,891

6 Claims. (Cl. 137—145)

The invention relates to a timing device for well intermitters so as to control the admission of pressure fluid by which the intermittent flow of the well is accomplished.

The present invention relates generally to that combination of structure shown in my prior co-pending application Serial No. 337,113 filed May 25, 1940, now Patent No. 2,339,487, granted January 18, 1944, for a Time and volume control for gas intermitters.

It is one of the objects of the invention to provide a particular form of timing device wherein the timing is varied by the removal and insertion of screws or other removable members so as to control the movement of a valve lever.

Another object of the invention is to provide an arrangement wherein pressure leaks constantly through the device and is effective to open the control valve when such leaking pressure is confined and permitted to build up sufficiently to open the valve.

Another object of the invention is to provide a combination timing and valve mechanism for gas intermitters.

Still another object of the invention is to provide a special timing disc having removable contact members.

Still another object of the invention is to provide a special form of adjustable valve lever.

Other and further objects of the invention will be more readily apparent when the following description is considered in connection with the accompanying drawing wherein:

Fig. 1 is a side elevation with certain parts in section showing the main valve, the control valve, and the operating parts;

Fig. 2 is a top plan view looking down on the timing unit;

Fig. 3 is a side elevation of the device of Fig. 2;

Fig. 4 is a section taken on the line 4—4 of Fig. 3 and illustrates an arrangement of the timing valve.

Fig. 1 illustrates the general set up and shows the same construction as is illustrated in the left hand side of Fig. 5 of my copending application.

The pressure fluid from a suitable source flows through a pipe line 2 through the power valve 5 and the pipe 4 whence it flows into the well. This power valve is of a particular construction including the valve member 3 which is disposed in a housing 6 and is operated by a stem 7. This is an upwardly closing valve normally held in closed position by a spring 8 and actuated by a diaphragm 9. This diaphragm operates in a chamber 10 formed by the flange 11 and the body 55

12 of the timing device. An entry port 13 into the chamber 10 admits pressure fluid so as to depress the diaphragm 9 and effect opening of the valve.

5 The timing mechanism is shown generally at 15 and is disposed in the housing 12. A connection 16 from the pressure line 2 extends through a suitable reducer valve 17 and the reduced pressure flows through the pipe 18 into the timing valve housing 19. The details of this timing valve construction 19 are best seen in Fig. 4. The pressure enters a chamber 20 in the housing 19 from the pipe 18 and flows from this chamber into a choke nipple having an opening 21 therein. This opening is controlled by an orifice 22 which governs the amount of flow from the pipe 18.

This pressure fluid will finally flow thru the opening 21 into the chamber 24 and escape from an outlet 25 therein under normal conditions.

20 A timing valve 27 is mounted on the pivot shaft 28 in the chamber 24 and the spring 29 tends to normally hold this valve against the end of the choke nipple, as seen in Fig. 4, to prevent any escape of pressure fluid into the chamber 24 and to close the passage 21. When this timing valve is thus closed, the pressure will build up in the nipple passage 21 and flow through the port 31 and recess 30 into the passage 37 and chamber 33 whence it can flow thru the outlet 35 to the port 13 to build up a pressure in the chamber 10 against the diaphragm 9 which will cause the valve to open. On the other hand, if the timing valve 27 is open the pressure will not build up and the valve will normally remain in closed position.

35 In order to control the movement of the timing valve 27, a lever 40 is affixed to the shaft 28, as seen in Fig. 2. This lever is of particular construction in that it includes a triangular head 41 which is suitably affixed upon the shaft by the shank 42. Mounted on this head for pivoting movement is the lever 43 pivoted on the screw 44. A slot 45 in the arm carries a setting screw 46 by which the lever can be adjusted relative to the head.

45 This lever has an upstanding rib 47 thereon which extends along the lever and is arranged to slidably receive the contact arm 48. This arm is adjustably mounted by the screw 49 and the slot 50. This arm has a contact finger 51 and a bevel face 52.

The lever has a plate portion 53 which is shown in Fig. 2 as being substantially flush with the edge of the finger 51 so that the contact face may include an inner edge of the finger 51 and the plate 53.

The spring 29 normally urges the valve 27 against the choke and this same spring normally urges the lever 43 in a clockwise direction (Figs. 2 and 4) toward the timing disc or plate 60. This plate is mounted upon a block or other power mechanism 61 enclosed in a housing 62 by which rotation of the spindle 63 is accomplished. The disc 60 is suitably affixed on the spindle 63. The disc 60 is shown as having a plurality of outstanding legs 64. This construction minimizes material and weight of the disc. In any event the disc carries a plurality of timing pins 65 arranged in spaced relation proximate its periphery. These pins are seen in side elevation in Fig. 3 and have a knurled head 66 and an intermediate area which is threaded in an opening in the disc 60, and a contact portion 67 which is arranged to engage the face 52 of the finger 51. It will be noted that the leg 68 has had the pin 65 removed therefrom and when this leg approaches the area of the finger 51, the spring 29 will cause the finger to move inwardly of the disc due to the urging of the spring 29. This movement allows the valve 27 to close and when the next succeeding timing pin engages the bevel face 52 as the disc rotates, the lever will be returned to the position shown in Fig. 2, overcoming the compression of the spring 29 and causing the timing valve 27 to again open. In other words, by adjusting the position of the finger 51, the time during which the timing valve 27 is closed can be controlled. If a long period of time is desired, more than one pin 65 can be removed and by adjustment of the finger 51 any desired proportion of the timing interval can be also adjusted. Thus, by manipulating the number of pins and the position of the finger 51, any desired timing can be accomplished. Different pins may be removed to obtain different periodic timing operations.

As pointed out before, when the valve 27 closes, the pressure builds up to open the power valve. It is to be noted that the finger 51 and the plate 53 arrangement is such that it will span the distance between the two pins to prevent its dropping in between them. If all of the pins are in place, the valve 27 will remain open and the power valve will remain closed. The pressure from the source would then continue to leak through the device and escape to the atmosphere. When the timing valve 27 closes, however, the mechanism is then placed in operation by opening the power valve.

Broadly, the invention contemplates a timing mechanism for well intermitters which can be readily adjusted to accomplish any desired timing interval.

What is claimed is:

1. In an intermitter timing device, a motor, a timing disc, a plurality of radially outstanding

5 circumferentially spaced legs thereon, a timing pin removably carried by each leg, and a timing valve normally held in open position by riding on said pins as said member rotates, and means tending to close said timing valve by moving said lever when a timing pin is removed from said member.

10 2. In an intermitter timing device, a motor, a timing disc, a plurality of radially outstanding circumferentially spaced legs thereon, a timing pin removably carried by each leg, and a timing valve normally held in open position by riding on said pins as said member rotates, and means tending to close said timing valve by moving said lever when a timing pin is removed from said member, said pins being removable so as to obtain such periodic timing of the intermitter as may be desired.

15 3. In an intermitter timing device, a timing member including a plurality of spaced removable timing pins, a lever, an arm on said lever to contact said pins and span the space between adjacent pins but to move into a space where one or more pins are removed, and means to adjust 20 the length of said arm to control the length of the timing period.

25 4. In an intermitter timing device, a motor, a timing disc, a plurality of circumferentially spaced openings therein, a timing pin removably carried by each opening, and a timing valve lever normally held in open position by riding on said pins as said member rotates, and means tending to close said timing valve by moving said lever when a timing pin is removed from said member.

30 5. A timing device for well intermitters, including a pivoted lever for controlling a timing period, a motor, a timer member turnable thereby, a plurality of circumferentially spaced radially outstanding legs on said member, a contact pin removably carried by each leg, said lever being normally forced against said pins and having an arm thereon to span the space between the adjacent pins on said member but to enter into a space where a pin is removed so as to thus move 35 40 45 said lever and means to vary the length of said arm to control the length of timing period.

6. A timing device for well intermitters including a pivoted lever for controlling a timing period, a motor, a timer member turnable thereby, a plurality of circumferentially spaced openings in said member, a contact pin removably carried by each opening, said lever being normally forced against said pins and having an arm thereon with a contact surface to span the space between adjacent pins on said member but adapted to enter into a space where a pin has been removed so as to thereby move said lever and means on said arm to vary the length of the contact surface to thereby control the length of timing period.

WILLIAM R. KING.
